ABSTRACT: A device for presenting weft yarns in continuous supply weft yarn looms having a hook lever for gripping and retaining the selected weft yarn swingably mounted on the loom sley and controlled by a cam and a second hook lever for retaining all the weft yarns swingably mounted on the fixed part of the loom and controlled by a second cam and for severing the selected weft yarn. The first and second hook levers coact to return an unsevered length of the selected weft yarn to the group of unselected weft yarns retained by the second hook lever.

LOOMS

This is a continuation of application Ser. No. 670,619, filed Sept. 26, 1967, and now abandoned.

BACKGROUND OF THE INVENTION

This invention relates to a weft yarn presentation device in continuous weft supply looms.

It is known that in continuous weft supply looms, wherein weft yarns are gripped at an end of the warp shed by a gripper or similar means carrying them to the middle of the shed where a second gripper in turn grips them to carry the same at the other end of the shed, selection and presentation devices are provided for weft yarns of a different colour, material and/or count, cooperating in making up the fabric. It is also known that these selection devices comprise a plurality of rods terminating in an eyelet at the free end thereof, a given weft yarn sliding within the eyelet of each rod. The rods are arranged to move one or more at a time from an inoperative position to an operative position (under the mechanical, or preferably electromechanical, control of punched board programming devices: Jaquard or Vincenzi systems), whereby the weft yarn or yarns carried thereby can be engaged by the device for presenting the weft yarn or yarns to the carrier gripper for the yarns of the loom.

As is known, presentation devices generally comprise a yarn gripping lever, means for retaining the gripped yarn at a position suitable for presentation to the gripper and subsequent displacement of said yarn as caused by the gripper, and a feeler for controlling the yarn continuity.

In heretofore known devices, the engagement and disengagement of weft yarns by said retaining means were always connected—owing to the structure and mounting position of such means on the fixed part of the loom—with the sley position with respect to the loom. Thus, said weft yarns will be engaged and/or disengaged at instants unsuitable for processing and, as a result, jammings or faults in manufacture will occur.

SUMMARY OF THE INVENTION

These disadvantages are now fully overcome by the improved presentation device according to the present invention, said device being of the type comprising a first gripping and retaining hook lever for the weft yarn as selected by the selecting device, a feeler, and a second retaining hook lever for all the weft yarns, and characterized in that said first lever and feeler are swingably mounted upstream of the warp shed, on the sley, while said second lever is swingably mounted on the fixed part of the loom, still upstream of the warp shed, but closer thereto than the first lever and feeler, said levers being oscillated by cams the rotation of which is controlled by the general mechanism for the loom. BRIEF DESCRIPTION OF THE DRAWINGS

The invention will now be disclosed in detail according to a preferred embodiment thereof, given merely by way of example and shown in the accompanying drawings, in which:

FIG. 1 is a perspective view of some portions of the loom as seen from the selecting device, with portions cut away and other portions broken away and the position and paths of the carriers shown by broken arrows when a weft thread is drawn across the path of one of the carriers for presentation to that one carrier; and

FIG. 2 is a view similar to that of FIG. 1, as seen from the median portion of the loom.

DESCRIPTION OF THE PREFERRED EMBODIMENT

Loom 1, to which the device according to the invention is applied, is fitted with a selecting device 2 having levers 3, within eyelets 4 of which weft yarns 5 slide from suitably braked supply cops or bobbins. In FIG. 2, only one of selecting levers 3_o has been operated to place its weft yarn 5_o at the disposal of the loom presentation means, and therefore at the disposal of the carrier gripper of the loom.

The improved presentation means according to the invention comprise a first hook lever 6 swingably mounted on sley 7

of loom 1; a feeler 8 in side by side relationship to said lever 6, and a second hook lever 9 acting also as a knife and swingably mounted on the fixed part of the loom 1 opposite lever 6 and feeler 8, but slightly nearer than the latter to the warp shed.

Oscillation of lever 6 is controlled by a cam 10 rotated by the general mechanism of the loom through a suitable drive. Cam 10 engages cam follower 11 of a rocking lever 12 controlling said hook lever 6 through two connecting rods 13, 15 and a second rocking lever 14.

Oscillation of hook lever 9 is similarly controlled by a cam 16 carried by the same shaft as cam 10 and engaging a cam follower 17 of a toggle lever 18 directly operating on hook lever 9.

The profile of cam 10 is of such a design that hook lever 6 will lower to grip the already selected yarn 5 prior to passage of the first carrier gripper of the loom past the point where said gripper should grip said yarn and will rise again to release the weft yarn when the end of the latter is about to be released by the other loom gripper at the opposite outlet of the shed. In turn, the profile of cam 16 is such that hook lever 9 will rise to release the weft yarns just after the entry of the grippers into the warp shed and will be lowered to grip again all the weft yarns upon the grippers reentering from the shed and while the sley is moving to tighten the weft yarn introduced into the fabric.

Under these circumstances, the operation of the device is apparent: once selecting lever 3_o has pushed a weft yarn 5_o into gripping position, the hook lever 6 will lower, gripping said yarn 5_o and arranging it at a suitable position for being gripped by the gripper which, cutting the yarn on the knife side of hook 9, drags it into the shed and exchanges it with the other gripper until the yarn is released from said second gripper at the opposite end of the shed. The knife side of hook 9 is of course its upstream side with respect to the direction of weft yarn travel toward the warp shed. While such release occurs, hook lever 6 will rise and between said selecting lever 3_o and shed entry said yarn 5_o will take on a straight stretched condition without being any more caused to retain the angled position shown in FIG. 2 and taken on after cutting and raising of lever 9. When sley 7 moves and tightens the just inserted weft yarn against the already manufactured fabric, said yarn will be therefore accurately stretched at its supply end and, as pushed by the sley action, will unfailingly join the other weft yarns inside of said hook of lever 9, the latter having lowered in the meantime, for being retained therein. In the subsequent steps, upon operation of the selecting levers the selected yarns are caused to take on the initial position.

Feeler 8 is held at a lowered position by said weft yarn 5_o, which depresses feeler 8 for all the period during which said hook lever 6 is lowered. Should the yarn break, the feeler will be released and on rising will stop the loom motor feed, causing this motor and the loom to be stopped.

As readily inferred from the above operation description, the improved device according to the invention avoids to the highest degree a frequent and detrimental drawback which is a distinctive feature of known devices. In fact, the possibility exists with the latter that the weft yarn would be unstretched at its supply end after being inserted in the warp and thus it may occur that it will not be gripped by the hook lever 9 and remain therefore at a position liable to be gripped by the lever 6 at the next cycle, even when this is not intended thus mixing with the selected weft yarn. This drawback of known devices results from the fact that yarn restraint (positively effected by lever 6 in this invention) was effected by a member fixed to the sley, which member released the yarn only after releasing of the driving end of said yarn, through the tightening movement of the sley.

In addition to preventing weft yarns from being incorrectly supplied, which usually results in their being undesirably mixed, or from giving rise to machine jammings, the device according to this invention also makes it possible to limit the braking torque exerted on weft supply cops or bobbins over the devices according to the prior art, wherein braking was also used for partially reducing the above drawback.

It should be noted that the braking reduction for the weft yarns enables a substantial increase in the loom speed with the obvious advantages resulting therefrom. Looms fitted with the device according to the invention will be, therefore, faster, more reliable, and more continuous when running and will permit the manufacturing of higher quality fabrics.

I claim:

1. In a loom having a frame and a lay including a reed through which warp threads pass which are formed into successive sheds which converge toward a fell and having a plurality of different weft threads extending from said fell to a plurality of stationary supply means, the lay having guide means thereon defining a path for a pair of carriers one of which engages a weft thread at a point adjacent an edge of the warp in the shedding area and carries it into the shed to a point intermediate the warp width at which point the other of which carriers completes the pick by drawing the weft into and across the remainder of the shed, means mounting the lay for movement on and relative to said frame alternately toward the fell to a forward position to beat the inserted weft threads into the fell and away from the fell to a retracted position, and a plurality of weft thread selectors on the loom through each of which a different weft thread passes between said supply means and the fell; the improvement comprising a first hook mounted on said lay to grasp a weft thread which has been selected by the associated said selector, at a point between said associated selector and the fell, a second hook mounted on the loom frame on the side of said path which is opposite the reed in said retracted lay position, means to move said second hook relative to said frame to grasp said selected thread at a point between said associated selector and the fell, and means to move said first hook relative to said lay in a forward position of said lay to grasp said selected thread at a point between said associated selector and the second hook and to draw said selected thread back across said carrier path as said lay moves from a forward position toward a retracted position with said selected thread crossing said carrier path

between said first and second hooks in said retracted lay position thereby to present said selected thread to said one carrier, said one carrier thereafter engaging said selected thread between said first and second hooks and drawing said selected thread about said second hook to sever the selected thread and carrying said selected thread into the shed with said selected thread guided by said first hook between said one carrier and said associated selector.

10 2. A loom as claimed in claim 1, wherein said means for moving said first hook are operative to raise said first hook out of engagement with said selected thread before the lay beats said selected thread into the fell.

15 3. A loom as claimed in claim 1, wherein said means for moving said second hook are operative to raise said second hook out of the path of said selected thread before the lay beats said selected thread into the fell.

20 4. A loom as claimed in claim 1, and a feeler mounted on the lay closely adjacent the first hook and lying in the path of and being depressable by that portion of a weft thread which is on the side of said first hook opposite said selectors, said feeler upon rising in response to a weft thread break being operable to stop the loom.

25 5. A loom as claimed in claim 1, said means for moving said first hook relative to the lay comprising means for lowering said first hook to grip said selected thread immediately after selection thereof and for maintaining said first hook lowered to guide said selected thread until the latter is completely inserted in the shed.

30 6. A loom as claimed in claim 1, said means for moving said second hook relative to the frame comprising means to raise said second hook out of the path of said selected thread before the lay beats said selected thread into the fell and for lowering said second hook again into a position to grasp a weft thread to be subsequently selected, upon movement of the lay toward the fell after the first-mentioned selected thread has passed said second hook.
